PRESSER FOOT FOR SEWING MACHINES

Charles W. Mueller, St. Louis, Mo., assignor to
 Lewis Invisible Stitch Machine Company, St.
 Louis, Mo., a corporation of Maine

Original application May 18, 1937, Serial No.
 143,387. Divided and this application January
 22, 1938, Serial No. 186,440

6 Claims. (Cl. 112—140)

This invention relates to new and useful improvements in sewing machine presser feet generally, although more particularly to a presser foot adapted for use in a blind stitch sewing machine.

5 This application constitutes a division of my copending application Serial No. 143,387, filed May 18, 1937, for improvements in Sewing machines.

10 The principal object of my invention is to provide a presser foot with a cloth retainer which is adjustable towards and from the needle, and an edge guide for the hem which is bodily movable with the retainer and is mounted thereon for transverse adjustments relative thereto.

15 With the above and other objects in view which will more fully appear, the nature of the invention will be more clearly understood by following the description, the appended claims, and the several views illustrated in the accompanying drawing.

20 In the drawing:

Figure 1 is an enlarged top plan view of a presser foot constructed in accordance with my invention and showing the hemmed cloth thereunder,

Figure 2 is a bottom plan view thereof,

Figure 3 is a perspective view of the cloth retainer, and

Figure 4 is a perspective view of the edge guide.

30 Like reference numerals designate corresponding parts throughout the several figures of the drawing.

Referring to the accompanying drawing, the presser foot B is provided with a longitudinally extending opening 28 through which the body fabric C being hemmed is projected upwardly by a ridge forming element (not shown) into position to be entered by the needle D which reciprocates centrally across said opening.

40 In order to retain the ridged fabric against the thrust of the needle, I have provided the presser foot B with a cloth retainer L which cooperates with the ridge forming element and is adjustable longitudinally with respect to the needle, and to

45 guide the inner edge of the hem fold in proper relation to the needle, I have mounted an edge guide M on the cloth retainer for transverse adjustments relative thereto. The foot is provided at its front end with a bearing lug 13 on the right 50 of the opening 28 of the foot. Mounted in this lug is a horizontally disposed split bushing 14 of steel which projects laterally from the side thereof opposite the opening 28 to form an extended bearing. A rock shaft 15 is journaled in the bearing and is provided at its inner end with

an eccentric pin 16. The outer end of the rock shaft is provided with a screw-driver slot by means of which the shaft may be rocked, and a set screw 18 is threadably engaged in the outer end of the bushing to retain the shaft in an adjusted position. The cloth retainer L is formed of thin spring steel, and the front end is provided with spaced bearing eyes 19, 19 which are journaled on the eccentric pin 16, and are retained thereon by a screw 20 which is threaded into the end of the pin. The cloth retainer extends rearwardly into the presser foot opening 28 directly above the ridge forming element, and the rear edge of the retainer is located immediately in front of the needle path, the retainer having a 10 stop portion 21 which overhangs the left edge of the presser foot opening and bears against the upper face of the foot to limit the downward movement of said retainer. A coil spring 22 is disposed around the eccentric pin 16 between the 15 bearing eyes 19, 19 of the retainer, one end of the spring bearing downwardly upon the retainer and the other end being anchored in a slot 23 of the bushing. It will, therefore, be seen that the spring yieldably holds the retainer against the 20 ridge of fabric which is formed by the ridge forming element, and consequently said ridged fabric is held by the retainer against the thrust of the needle. The edge guide M includes a horizontal supporting arm 24 having a slot 25 and is mounted 25 on the cloth retainer L for transverse adjustments relative thereto. A screw 26 passes through the slot 25 and into the retainer and functions to retain the guide in any position of adjustment. Integral with the left end of the arm 24 is a 30 depending and forwardly extending edge guiding finger 27 which extends rearwardly along and projects below the left hand edge of the retainer L. From the above, it will be observed that the retainer L can be adjusted towards or from the 35 needle path to meet different working conditions; that the edge guide M will be adjusted therewith, and that the edge guide is adjustable transversely relative to the retainer.

40 It will be observed by reference to Figure 3 of the drawing that the retainer member L has a laterally directed slot therein. The edge guide shown in detail in Figure 4, and which is mounted for transverse adjustments on the member L includes a shank portion which depends from the arm portion 24 so as to be projected through and movable in said slot.

45 It is of course to be understood that the details of structure and arrangement of parts may be 50 55

variously changed and modified without departing from the spirit and scope of my invention.

I claim:

- 5 1. A presser foot having an elongated opening, a cloth retainer mounted on the foot and projecting into said opening, means for imparting to said retainer movements of adjustment in the direction of the length of said opening and for securing said retainer in its various positions of adjustment, and an edge guide mounted on said retainer for transverse adjustments relative thereto.
- 10 2. A presser foot having an elongated opening, a cloth retainer mounted on the foot and projecting into said opening, means for imparting to said retainer movements of adjustment in the direction of the length of said opening and for securing said retainer in its various positions of adjustment, and an edge guide substantially co-extensive in length with and mounted on said retainer for transverse adjustments relative thereto and projecting downwardly into said opening below said retainer.
- 15 3. A presser foot having an elongated opening, a cloth retainer pivoted on an eccentric pin supported above said foot and projecting into said opening, said pin being adjustable for altering the position of the retainer in said opening, spring means for urging the retainer downwardly, a stop fixed to the retainer and overhanging the foot along side said opening to limit the downward movement of said retainer, and an edge guide mounted on said retainer for transverse adjustments relative thereto and projecting downwardly into said opening below said retainer.
- 20 35

4. A presser foot having an elongated opening and an upstanding transversely disposed bearing, a shaft rockably mounted in the bearing and having an eccentric pin portion movable about the axis of said shaft when the shaft is rocked about its axis, and a spring pressed cloth retainer supported on the pin portion and projected into the opening for adjustment longitudinally therein.

5. A presser foot having an elongated opening and an upstanding transversely disposed bearing, a shaft rockably mounted in the bearing and having an eccentric pin portion movable about the axis of said shaft when the shaft is rocked about its axis, a spring pressed cloth retainer supported on the pin portion and projected into the opening for adjustment longitudinally therein, and an edge guide mounted on said retainer for transverse adjustments relative thereto and projecting downwardly into said opening below said retainer.

6. A presser foot having an elongated opening and an upstanding transversely disposed bearing, a shaft rockably mounted in the bearing and having an eccentric pin portion movable about the axis of said shaft when the shaft is rocked about its axis, a spring pressed cloth retainer supported on the pin portion and projected into the opening for adjustment longitudinally therein and having a laterally directed slot therein, and an edge guide mounted on said retainer for transverse adjustments relative thereto and projecting downwardly into said opening below said retainer and including a depending shank portion projected through and movable in said slot.

CHARLES W. MUELLER.
